UNITED STATES PATENT OFFICE.

AUGUST BIELE, OF NEW HAVEN, MISSOURI.

INSULATOR.

No. 823,912.

Specification of Letters Patent.

Patented June 19, 1906.

Application filed July 25, 1905. Serial No. 271,220.

To all whom it may concern:

Be it known that I, AUGUST BIELE, a citizen of the United States, residing at New Haven, in the county of Franklin and State 5 of Missouri, have invented new and useful Improvements in Insulators, of which the following is a specification.

My invention has relation to that class of insulators that are connected with the cross-arms of telegraph-poles to support the line-wires of the telegraph; and it has for its object the provision of improvements whereby pins are done away with for supporting the glass knobs usually employed; the insulator 15 is less liable to be broken or shot to pieces by mischievous boys with toy guns and slings; it is inclosed in the arm, so as to be protected; the wire is not liable to fall to the ground if the insulator should be broken; it can 20 readily be made to suit an arm or wire of any size; it is more economical than the screw-threaded pin and knob; it is more safely tied in quick time than by the knob and tie; can be employed at either the top or bottom 25 of the cross-arm; can be easily and quickly replaced in case of necessity.

The drawings are an essential part of this specification and are to be referred to as such, and represent, in—

30 Figure 1, a perspective view of a pole and cross-arm equipped with my improved insulators. Fig. 2 is a perspective view of one of my improved insulators detached. Fig. 3 is a longitudinal sectional view of the cross-arm with the insulator secured therein. Fig. 4 is an end view.

My improved insulator is preferably employed near the edge of the cross-arm and when so used may be introduced near the 40 lower or upper edge, as may seem best. It is constructed of glass and may be made round or cylindrical in form, with one or more holes *a* made longitudinally through it for a line-wire or line-wires and another hole *b* 45 for the tie-wire. For that matter, one or more cylindrical grooves *c* may be formed in the outside for the tie-wires. A slit *d* will be formed longitudinally in the insulator from the outside to the hole *a*, so that the line-

wire may be simply laid therein through a 50 slit *e*, made in the cross-arm from the outside to the hole *f*, which may be bored through the arm as near the edge as may be wanted.

After the line-wire is put in place in the insulator the latter may be turned slightly to 55 keep the line-wire from accidentally dropping out, and to maintain it from turning or from otherwise becoming displaced a long-shanked nail *g* may be driven into the cross-arm and the transverse groove in the side of 60 the insulator, and so key the latter in position. Any other suitable means may be employed for this purpose. After all of the parts are in place, as stated, the tie-wire *h*, 65 passing through the hole *b* or laid in the groove *c*, may be twisted around the line-wire or its supports in any suitable and convenient way to hold it in place and not disturb its insulation. The hole *e* for the insulator may be bored through the cross-arm, 70 at or near its center; but in that case the slit *f* would have to cut through a good deal of the substance forming the cross-arm. But little time is required to slip the line-wire through the slit in the cross-arm and sides of 75 the insulator, and when the insulator is keyed and the line-wire tied, which can be done in an inconsiderable amount of time, all things are as securely in place as need be. The line-wire may be taken out without cutting 80 the line-wire, and repairs or changes can be made in an entirely practical way and most expeditiously. As before stated, the line-wire is not likely to fall to the ground or get out of the way, so as to cause accidents. 85

Changes may be made in the form and arrangement of parts within the limits of mechanical skill without departing from the nature or spirit of the invention.

I claim—

90 A device of the character described, comprising an insulating-block having a longitudinal groove or passage opening out laterally therethrough, also an additional longitudinal passage, said passages receiving 95 the line-wire and a tie-wire for the latter, respectively, said block being arranged in a bore or opening in an arm or tree of a

telegraph - wire or other pole and adapted to permit the insertion of said line - wire through it into said block, a plate effective for the closure of the entrance to the initial line - wire - receiving passage, said closure-plate having an aperture through it and said block having also a transverse passage in its outer edge, and a key insertible through said

plate or closure-aperture and said transverse passage of the block.

In testimony whereof I affix my signature in presence of two subscribing witnesses.

AUGUST BIELE.
